UNITED STATES PATENT OFFICE.

PAUL L. CROWE, OF JERSEY CITY, NEW JERSEY.

CHAIN-GRADE MECHANISM.

1,168,712.

Specification of Letters Patent. Patented Jan. 18, 1916.

Application filed May 6, 1909. Serial No. 494,815.

To all whom it may concern:

Be it known that I, PAUL L. CROWE, citizen of the United States, and resident of Jersey City, in the county of Hudson and State of New Jersey, have invented certain new and useful Improvements in Chain-Grade Mechanisms, of which the following is a specification.

My invention relates to chain grate mechanical stokers, and the object is to provide a stoker with new and useful mechanisms for increasing stoker and furnace efficiencies.

Further objects are: To provide means for automatically releasing the driving power whenever the traveling grate is checked or stopped by an excess of load or other causes. To provide means for carrying the grate bars on the traveling chain for giving the grate surface an undulating motion for facilitating and increasing the combustion of the fuel. To provide means for retaining the links of the cable chain at an angle of 45° to the horizontal when the chain grate is moved. To provide means for carrying specially fine fuel on a burning surface having fine air spaces. To provide means for distributing the fuel on the traveling grate to the proper thickness. To provide means for delivering the ashes on the dump plate, and mounting and operating the dump plate. To regulate the uneven rolling surface of the traveling chain. To provide means for taking up the slack of the grate chain.

Referring to the drawings: Figure 1 is a side elevation partly in section of my mechanical stoker embodying my improvements. Fig. 2 is a front elevation partly in section. Fig. 3 is cross section of the furnace showing the sprocket wheels, grate bars, traveling chain, roller, and angle iron side plates. Fig. 4 is a cross section of one end of the bars attached to a chain having links positioned at an angle of 45° to the horizontal, on the grooved intermediate peddlers. Fig. 5 is a detached view of one of the grate bars attached to a chain having links positioned at a 45 degree angle to the horizontal, and also the grooved intermediate peddlers. Fig. 6 is an enlarged fragmentary view of the side of the furnace showing the adjustable bearing. Fig.

7 is a front view of the furnace showing adjustable bearing. Fig. 8 is a fragmentary view of the top of one of the adjustable bearings. Fig. 9 is a view of one of the sprocket wheels detached from the stoker. Fig. 10 is a cross section of one of the sprocket wheels showing the chain upon same, and three grate bars on said chain. Fig. 11 is a perspective view of one of the grate bars. Fig. 12 is a bottom view of three of the grate bars attached to the traveling chains. Fig. 13 is a perspective fragmentary view of the dump plate mechanism. Fig. 14 is a side view of the dump plate mechanism. Fig. 15 is a plan view of the dump plate with dump plate frame removed. Fig. 16 is a fragmentary side view, partly in section, of the front end of the furnace showing the fuel hopper adjusting mechanism in a raised position. Fig. 17 is a side elevation of the automatic power releasing mechanism. Fig. 18 is an end view of Fig. 17. Fig. 19 is an enlarged sectional view of the power releaser as shown in Fig. 17, with externally threaded ball stem. Fig. 20 is a section on line A—B, Fig. 19. Fig. 21 is a section on line C—D, Fig. 19. Fig. 22 is a section on line E—F, Fig. 19. Fig. 23 is a sectional elevation of the power releaser with exterior threaded ball stem.

Fig. 24 is a sectional elevation of the lower portion of the power releaser. Fig. 25 is a detached elevation of the dump plate operating arm. Fig. 26 is a sectional view showing the manner the shield is secured to the under side of the upper angle irons.

The furnace 2 supports angle irons 3—4, which are supported intermediately by standard 5. 6 are the traveling chains. Each link of said chains is set at an angle of 45 degrees. The chains travel over the sprocket wheels 7 and grooved wheels 8. The grooved wheels are mounted on rods 9 supported by the angle irons 3. The sprocket wheels 7 are mounted on the shaft 10, which is supported in movable bearings 11, slidably mounted, between the upper and lower portions of the housing 12, which is secured to the front of the furnace. These movable bearings are adjusted and held by pins 13, inserted into holes 14, cut in the angle iron 15, which is secured to the lower half of the housing. The upper half of the housing at

15^a is also provided with holes staggered in position for finer adjustment of the movable bearing by insertion of pins. The adjustable bearings permit the chains being readily tightened should they become slackened from use.

Each sprocket wheel comprises a hub 7, which forms the bulk of the wheel. At or near the outer end of the hub are formed 10 the sprocket grooves 17 conforming to the longitudinal contour of the links 6 of the chain. Said sprocket grooves are formed to retain the links of the said chain at a 45 degree angle. The angle of said links of 15 the chains 6 necessitates the forming of a double row of sprocket grooves 17 around the wheel, each groove being in a staggered position to each other in the contour of the said wheel.

20 In the contour of the sprocket and between the ends of the grooves are formed recesses 19, said recesses receiving the lower ends of the downwardly projecting hooks 20 on the grate bars 22.

25 The diameter of the hub 7 is proportioned so as to form the enlarged portion 23, on each side of the sprocket grooves, giving ample strength to the sprockets formed by the grooves. The hub 7 is given a sufficient length on one side of the grooves to insure substantiability on the shaft, and also a sufficient key surface thereon.

30 The recesses 19, formed in the periphery of the wheel are adapted to accommodate 35 the chain engaging hooks 20 of the grate bars. These hooks extend into the links of each chain but do not interfere with the operation of said chain because of the recesses in the construction of the sprocket wheels. 40 This construction forms a very desirable means for operating a traveling grate, being simple and strong, and allowing the grate bars to be easily detached and replaced on the chains.

45 Each of the links of the chains 6 support a grate bar 22, one end 24 of which being secured to a link by an integral hook or nose 20 extending downward. The other end of the grate bar is attached to a link by a divided detachable pin 25, extending 50 downward on an incline. The upper end of this pin 25 extends upward from the links into the grate bar 25^a and is held to the said grate bar by a cotter pin passing through holes in the stem of the said grate bar and holes in the upper portion of the divided detachable pin. This mode of securing the grate bar to the chains is alternately arranged (see Fig. 12), tending thereby to secure the links of the chains loosely in a 45 degree position. As the bars travel through the combustion chamber with the traveling chains, they have an individual movement, that is, raised and lowered alternately by 65 the links of the chains, as the said links

pass over the intermediate peddler wheels 26, which are mounted on the rods 27, secured to the angle iron 3. Each of the peddlers 26 is provided with an enlarged portion 28, and a grooved portion 29 (see Fig. 70 5). Now as one of the links passes over the enlarged portion 28 of the peddler, it will hold the end of the bar attached to that link up higher than the rest of the bars, but when the following link passes into the 75 groove 29 of the peddler, it will lower the end of the next bar attached to the depressed link, or vice versa.

The grate bars are each provided with fingers 30, web 31, and stem 32. Between 80 the stem of one bar and the fingers of the adjoining bar the space 33 is narrowed so as to form fine or small air spaces for carrying the fuel in combustion.

The grate bars travel over the rollers 34 85 when returning. The rollers 34 are each made hollow with solid heads, and are intended to revolve loosely on the shaft or rod 36, which is supported by the angle iron 4. The fuel is fed upon the grate bars 90 through the hopper 37 secured to the furnace front. Within the hopper is pivotally mounted the hopper plate 38, which is raised and lowered by the arm 39, which in turn is pivotally supported at each end in the upper portion of the housing. To one end of the arm 39 outside of the housing is attached a lever 40 which is used for turning 95 said arm in order to adjust the position of the hopper plate 38 in the hopper. 100

On the top of the hopper plate 38 is mounted the sliding plate 41 held in position thereon by slots cut in said sliding plate, and also by studs fastened in the hopper plate. The sliding plate 41 is slid up and 105 down on the hopper plate by the crank arm 42 mounted on the shaft 43 supporting the hopper plate, and this crank is connected to the sliding plate by links 44. On the outside of the crank arm shaft 43 is mounted a lever 110 45, and by moving same the slide may be drawn upward or downward on the hopper plate the required distance. (See Figs. 1 and 16.) The object of the hopper plate and its sliding plate is to regulate the thickness 115 of the fuel on the grate surface. The sliding plate when operated regulates the hopper plate's position to the fuel when said plate is raised or lowered. When the hopper plate is raised and its sliding plate drawn 120 up, the interior of the furnace is readily accessible.

125 50 is the dump plate frame pivoted on the angle iron 3. Said frame carries the shaft 51 upon which are mounted and also oscillate the lap bars 60, the inner ends of which rest on the surfaces of the grate bars 22. The ends of the lap bars are united by a tongued and grooved connection 62. (See 130 Figs. 1-4.) 132

70 is the dump plate mounted on the pivoted shaft 72^b (see Figs. 13 and 14) mounted in the angle iron 3. On the dump plate frame 50 is fastened the lever 53 extending 5 underneath the same. An offset 72^a is cut in the dump plate at each end so that when the dump plate is opened, the shoulder 74 of the offset will depress the lever 53 and tilt the dump plate frame upward for producing an upward and downward eccentric motion to the rear of the lap bars.

The dump plate 70 is operated by the rod 75 pivoted in the lower angle iron 4. The upper member 76 of said rod is bent at right angles so as to rest on the under side of the dump plate (see Figs. 25 and 2). The lower member 77 of said rod is connected to one end of an operating angle bar 72 which is connected at the opposite end to a crank 20 arm 78 on stud 79, which is supported on the lower portion of the housing. This stud 79 is provided with a square end to receive a lever arm 71 by means of which the said dump plate can be raised or lowered.

25 The sprocket wheel shaft 10 has mounted on one end of it the gear box 80, which supports the ratchet wheel shaft 81, the ratchet wheel 82, and the divided bracket 83. The bracket 83 supports the pawl 84, and contains the ball bearing 85. This divided bracket is held together by bolts. To the divided bracket is attached the power releaser 90 (see Figs. 17 to 24). This regulator is connected to the hollow eccentric rod 92 35 which is attached to the motor for driving the stoker. The lower extension of the rod 92 is attached to the upper head 93. This head is attached to a spring 94. The lower end of this spring is attached to the lower 40 head 95. Both of these heads have central openings, through which pass the ball stem 96. To the lower end of this stem is secured a ball 97, which is intended to operate in the ball bearing seat of the divided bracket 83. 45 The stem 96 is provided with a slot 98. The head 93 has an aperture 99 with locking portion 100.

When the grate is obstructed, it should be understood that the spring 94 in the form 50 shown in Fig. 19 will be compressed and the hook formed on the lever 102 will move in the slot in the head 93, thereby merely causing the tube 92 to compress the spring without moving the arm 83. In the form 55 shown in Fig. 23, the spring 90 will be compressed when the grate is obstructed since the head 90' will be forced downwardly upon the spring 90, and the lever 91' will be forced out of contact with the collar 92'. 60 The collar, will however, limit the outward movement of the head 90' as the lever 91' will come in contact therewith as is clearly shown in Fig. 23.

65 102 is a locking lever pivoted to either heads 93—95. This lever has a locking por-

tion which engages with the locking portions of either head. (See Fig. 19 for upper locking and Fig. 24 for lower locking). The locking portion of the lever 102 is adapted to enter a suitable slot in the head 93.

70

105 is an adjustable nut threaded on the ball stem 96.

106 is a lock nut. Between the lower head 95 and adjustable nut 105 is positioned a cushion for taking up the shock.

75

In case of any obstruction to the working of the stoker, the excess of pressure on the spring 94 in consequence thereof will necessarily compress same. This will release the locking portion of the heads from the locking portion of the lever 102, which instantly separates itself from the heads and allows the tubular rod to move freely on the ball stem which will now cease to move and remain at rest. No action is now produced 80 on the ratchet wheel and no motion is transmitted to the traveling chain. The power can continue in motion and the stoker is inoperative. As soon as the obstruction is removed the lever is brought back into place 85 on the heads and the power again transmitted to the stem, ratchet wheel and stoker as before.

The modified form of power releaser in Fig. 23 shows the locking lever attached 95 to the upper head and locks into an annular groove in the lower head.

Instead of having the strain of the power exerted on the threads of the stem as in Fig. 19, I, in Fig. 24, have transferred it 100 into a separate head, 206, which is integral with the stem, for adjusting the extension of the stem, the threads are internally positioned in the head, which is also the ball stem.

105

Underneath the upper angle iron 3 is positioned the air shield 120 (see Figs. 1 and 26). This shield is connected to said angle iron by bolts 121, and is positioned on same at the front of the furnace. This shield 110 prevents the air passing through the grate bars 22 into the green fuel, so that the fuel may more readily ignite at that portion of the furnace. The shielding of the air prevents the radiation of the heat from the 115 arch above the grate bars being reduced.

The lower portions of the housing 12 are made triangular in shape and are supported by the angle iron 12^a. Said angle 12^a is positioned vertically on the boiler front 2^a, 120 Fig. 1. The upper portion of the housing 12 is connected to the angle iron 12^a which forms the ends of the fuel hopper and the upper guide to the front shaft bearing 11.

The hook and socket portions of the grate 125 bar at the opposite ends thereof 21 are flared outward and above the curved portions of the grate chain links forming shoulders 21^a, which cause the bar to rest in a right angled position to the chain, the lower 130

hollow portions of these shoulders formed on each side of the bar being adapted and conform with the contour of the ends of the links of the said chains.

5. What I claim is:

1. The combination of a traveling grate, means for operating said grate including mechanism for releasing the power from said traveling chain grate when said grate is unduly obstructed, consisting of an upper and lower head piece having each a central orifice, a coil spring engaging said heads, a locking lever pivotally mounted on one of said heads and adapted to engage the other head for releasing said lever when said grate is obstructed, a guide tube secured to said upper head, a stem passing through said tube and heads, said stem attached to the actuating mechanism of said traveling grate, and said tube connected to the rod driving mechanism of the stoker.

2. The combination of a traveling grate frame, chain supporting rollers similarly positioned in said frame, each roller having a plane and a grooved portion, a chain grate mounted in the grate frame comprising grate bars, chains upon which the bars are mounted, the chains in operative position having links positioned at substantially 45° to the horizontal, said links supported on the rollers with the alternate links engaging the grooved portions of the roller, and the other links engaging the plane portions whereby the grate is given an undulating motion as it travels along the grate frame.

3. In a stoker mechanism, a furnace, upper and lower angle irons mounted within said furnace, a dump plate frame pivoted on said upper angle iron, a dump plate pivoted on said angle iron adapted to act against said dump plate frame, means for opening and closing said dump plate comprising a rod pivoted to the lower angle iron, said rod having an upper and a lower member, said upper member resting against the upper side of said plate, said lower member pivotally connected to the operating angle bar, a lever fulcrumed on the outside of said furnace, said operating bar connected to said lever, means for tilting said frame, and means for feeding ashes on said dump plate consisting of a progressive feed grate operating within the furnace, means for operating said grate.

4. In a stoker mechanism, a furnace, upper and lower angle irons mounted within said furnace, a shaft pivotally mounted on said upper angle irons, a dump plate frame mounted on said shaft, lap bars loosely pivoted on said frame, a dump plate having end off-set, a lever arm mounted on said frame, said arm passing into said off-set in said dump plate, so that said plate when open will depress said lever thereby automatically agitate said frame and lap bars, means for

opening and closing said dump plate, and means for feeding ashes on said dump plate consisting of the progressive feed grate of said stoker.

5. In a stoker mechanism comprising a furnace, a grate mounted therein, upper and lower angle irons mounted within said furnace, a divided housing, a housing secured to said furnace on the outside of same, the lower members of said divided housing being triangular in shape, the upper portion of said housing comprising a fuel hopper, mechanism for feeding the fuel in said housing hopper, consisting of a hopper plate pivotally mounted in said housing hopper, a sliding plate mounted on said hopper plate, means for moving said sliding plate consisting of a lever arm pivotally connected to said plate and fulcrumed within said housing, means of raising and lowering the lower end of said hopper plate consisting of an arm mounted on a fulcrumed lever, said arm adapted to act against the underside of said hopper plate, said lever of said arm adapted to be operated outside said housing hopper.

6. The combination of a traveling grate frame, chain supporting rollers mounted thereon, each roller provided with a plane and grooved portion, a chain grate mounted in the grate frame, said chain provided with links positioned at substantially 45° to the horizontal axis of said links, the alternate links engaging the grooved portions of the rollers, and the other links engaging the plane portions thereof, whereby the grate is given an undulating motion as the same travels along the grate frame.

7. The combination of a traveling grate frame, rollers carried thereby, sprockets carried thereby, a chain grate working upon said rollers and sprockets, said chain grate having the links thereof extending at an angle substantially 45° to the horizontal axis of said rollers and sprockets, grate bars carried by said chain grate, and said rollers provided with means for causing said chain grate and grate bars to be given an undulating motion as the same travel along the grate frame.

8. In a device of the class described, an endless traveling grate, an endless chain, a frame, sprocket wheels carried by said frame, said chain traveling over said sprocket wheels and comprising links extending approximately 45° to the horizontal axis of the chain, said sprocket wheels provided with means for interlocking with the links of said chain, grate bars, each grate bar provided with a downwardly extending connecting ear for fitting in one of said links of said chain and holding the same against lateral movement relative to said chain, and peddler wheels arranged beneath the grate, said peddler wheels being so con-

structed as to give an undulatory motion to the grate bars as the same travel along said grate frame.

9. The combination of a traveling grate frame, a chain grate, said grate comprising a plurality of chains having links arranged at 45° to the horizontal axis thereof, grate bars carried by said grate chains, each grate bar provided with an ear extending downwardly at an angle of approximately 45° to the longitudinal axis of the bar, and said ear provided with an enlarged portion upon its inner face for interlocking in the links of one of said chains whereby said grate bar is held against transverse movement relative to said chain.

10. The combination of a traveling grate frame, a chain grate comprising a plurality of chains, the links of said chains arranged at an angle of approximately 45° to the hori-

zontal axis thereof, grate bars carried thereby, each grate bar provided with an integral depending ear at one end extending downwardly at an angle of approximately 45° to the horizontal axis of said grate bar, and 25 a detachable ear at the opposite end of said grate bar, each integral ear being provided with an enlarged knob upon its inner face adjacent the lower end thereof for interlocking in a link of one of said chains and 30 holding said bar against transverse movement relative to said chain.

Signed at Jersey City in the county of Hudson and State of New Jersey this 4th day of May A. D. 1909.

PAUL L. CROWE.
